UNITED STATES PATENT OFFICE.

WILLIAM P. MARTIN, OF NEW YORK, N. Y.

STEREOTYPE-PLATE HOLDER.

SPECIFICATION forming part of Letters Patent No. 361,306, dated April 19, 1887.

Application filed July 2, 1886. Serial No. 206,954. (No model.)

To all whom it may concern:

Be it known that I, WILLIAM P. MARTIN, residing at New York, in the county of New York and State of New York, have invented 5 certain new and useful Improvements in Stereotype-Plate Holders, of which the following is a specification, reference being had therein to the accompanying drawings.

This invention relates to stereotype-plate 10 holders, and is more especially intended for use with stereotype or other plates which may require to be adjusted off the center, sides, or corners of the holding or base block.

In the drawings, Figure 1 is a plan or face 15 view of the device complete. Fig. 2 is a section on line *x x*, Fig. 1.

A indicates the stereotype-plate holder, which has preferably a wooden body bound with metal; but the body portion may be of 20 metal, if desired.

The letters B B, &c., indicate grooves in the 25 plate-holder. These grooves extend inwardly from the sides and ends of the plate-holder, but do not extend entirely across the same. The end grooves are in position parallel with the sides of the block or plate-holder, and the side grooves are parallel with the ends of the block.

In each groove there is a swiveled screw- 30 threaded rod, C, and this rod bears a clamp, D, which engages the edge of the plate in usual manner. The screw-shaft C is turned by means of a rack-engaging pinion, E, as is well known in the art, to move the clamp D toward or away 35 from the medial line of the block. Each screw-rod and clamp is similar to such as have been used heretofore.

There should be, by preference, three clamps and rods on the side of each block or plate- 40 holder and two at each end. Then, if the center of the plate is brought to the proper position by the two middle clamps, the ends can be moved to position a little oblique to the sides of the block, and there retained by the 45 other clamps. This is sometimes necessary in registering plates in the form, especially in colored work.

It is a frequent practice to nail or tack ste-

reotype or electrotype plates to the blocks on which they are mounted, this being considered 50 necessary owing to variation in the size or proportion of the plates in the form. When so secured, the plates cannot be raised or moved for the purpose of underlaying or to correct 55 false register.

With my device fine adjustment may be made to any possible position on the block and with great facility without disturbing the blocks or plate-holders in the forms.

The face of the plate-holder has an index 60 consisting of a number of lines parallel with the sides and ends. The lines should preferably be ruled at distances apart equal to multiples of some standard type-body—as nonpareil or pica—and may be numbered or lettered. 65

I am aware that a stereotype-plate holder has been patented in which there are swiveled rods provided with right and left screw-clamps extending across the block. This precludes placing of the stereotype in any other than a 70 central position on the plate-holder.

An extensible or composite plate-holder has also been patented in which the clamps on all sides of the plate-holder were independent, but a portion of the plate-holder was made to 75 move with the clamp. This form of plate-holder would not permit of the adjustment of the plate to any but a central position without changing the furniture.

My plate-holder or block can be made up as 80 a page in a form and the plates and size thereof changed at will and adjusted to any desired position on the holder-block without unlocking the form.

I claim—

A stereotype-plate holder having marginal 85 clamps and having indicating-marks on its face to designate the position of the plate relatively to the margin, substantially as described.

In testimony whereof I affix my signature in 90 presence of two witnesses.

WILLIAM P. MARTIN.
